HELICAL PULP GRINDER

Loyal H. Hess and Lloyd Hornbostel, Beloit, Wis., assignees to Beloit Iron Works, Beloit, Wis., a corporation of Wisconsin

Filed Oct. 28, 1959, Ser. No. 849,349
10 Claims. (Cl. 241—279)

The present invention relates broadly to the art of pulp production for use in paper manufacture, and is more particularly concerned with new and improved log disintegrating apparatus employing conical abrasive means engageable with axially movable logs, the apparatus featuring in part independently operable, accurately controllable and infinitely adjustable abrasive means.

It has heretofore been proposed to support a log to be ground in a horizontal position upon a pair of spaced non-driven rollers and to subject the logs to a shredding action by means of a conical grinding wheel, which functions to abrade, rotate and axially advance the log through successive grinding stations. While the pulp grinding machine to which reference was made represents a substantial advance over the prior art, it has been found that numerous improvements can be made therein to enhance the versatility of the apparatus to improve upon the efficiency of the pulp grinding operation and to produce pulp stock of higher quality for paper manufacture.

It is accordingly an important aim of the present invention to provide a helical pulp grinder having as one feature thereof a plurality of grinding members each mounted by individual driving means and thereby permitting selective control over the abrading action performed in different grinding stations, and further eliminating the necessity of relatively cumbersome intermediate drive linkages.

Another object of this invention lies in the provision of log abrading apparatus utilizing a plurality of spaced grinding units, each of which is adjustable in a plurality of different planes to permit accurate control of the force applied for different types of woods being ground as well as use with a wide variety of log diameters, and further permitting relative movement of a particular point on the grinding surface with respect to the top center of the log whereby longer grinding surface wear is obtained.

Another object of the instant invention is to provide grinding apparatus for producing pulp from axially advancing logs, and which comprises a plurality of grinding units, means pivotally mounting each of the grinding units upon a stationary support, and pneumatic means connecting with the mounting means to pivotally swing each grinding unit through an arcuate path toward and away from the logs supported therebeneath.

A further object of the present invention is to provide grinding apparatus of the character described, and which additionally features enclosure means for the grinding units to protect the drive means and particular connecting structure against damage from treating fluid used in the grinding operation, as well as to prevent splashing of adjacent personnel by said fluid and pulp contained therein.

An even further object of this invention lies in the provision of pulp grinding apparatus, and which additionally features vertically and horizontally adjustable supporting rollers for the logs during the grinding thereof, whereby logs of varying diameters can be accommodated and uniform compressive forces exerted thereagainst to assure loosening of the log fibers regardless of the log diameter.

Other objects and advantages of the invention will become more apparent during the course of the following description, particularly when taken in connection with the accompanying drawings.

2

In the drawings, wherein like numerals designate like parts throughout the same:

FIGURE 1 is an end elevational view of grinding apparatus constructed in accordance with the principles of this invention, and showing the grinding unit in a position of engagement with the log being ground;

FIGURE 2 is a view similar to FIGURE 1, and showing the grinding unit in a raised or retracted position relative to the log;

FIGURE 3 is a fragmentary side elevational view of the present grinding apparatus, illustrating the successive diameter reductions effected upon a log during travel axially upon supporting rollers;

FIGURE 4 is a sectional view taken substantially along the line IV—IV of FIGURE 1, and showing particularly an exemplary form of stock means which may be employed to limit upward and downward swinging movement of the grinding units;

FIGURE 5 is a fragmentary sectional view taken substantially along the line V—V of FIGURE 1, and illustrating means for adjusting movement of the grinding wheel motor mount with respect to supporting structure therefor; and

FIGURE 6 is a view taken substantially along the line VI—VI of FIGURE 1, and showing in further detail vertical and tiltable adjusting means as provided in accordance with the novel concepts of this invention.

Briefly stated, grinding apparatus as herein provided embodies a plurality of individual abrading mechanisms which act upon spaced locations of rotating and axially advancing logs supported by roller means having vertical and horizontal adjustability as a feature thereof. The rollers and the logs carried thereon are partially submerged in a bath of treating fluid housed in a trough, the treating fluid having among its purposes a loosening of the log fibers to facilitate separation during the grinding operation. The trough is enclosed when the log abrading is taking place, and the enclosure means protects the grinding units and persons in the area adjacent thereto against splashing effects from wet pulp and/or treating solution.

Each grinding unit is preferably mounted by a stationary support carried by the trough structure, and the stationary support receives pivot means mounting a swingable stop member which cooperates with a stationary stop member fixed to the supporting structure. The swingable stop member connects with supporting means mounting the grinding units and associated with the supporting means are pneumatic motive means or cylinders, the actuation of which swings the movable stop member, connecting supporting means and associated abrading surfaces about the fixed pivot on the stationary support to raise or lower the grinding surfaces as desired.

Each grinding surface is preferably in the form of a conical grinding wheel mounted by an individual motor, which is in turn connected to the supporting means and features vertical adjustability relative thereto. Each grinding motor and the grinding wheel carried thereby is further adjustable in a direction generally transverse to the log top center to change the point of tangential contact of the grinding surface or wheel on the log periphery. Additionally, each grinding motor is tiltably adjustable upon the supporting means to provide a further variation in the point of tangential contact of the grinding surface on the log, as well as a fine control over the force applied to the log during the grinding operation. Numerous other features of the invention will become more apparent as the description now proceeds.

Grinding apparatus provided in accordance with the principles of this invention is designated generally in FIGURE 1 by the legend A, and comprises a supporting base 10 which may be of cement construction and formed

to provide a longitudinally extending central portion 11 at opposite sides of which is a pair of trough portions 12 and 13 wherein may be located a treating fluid in a quantity sufficient to fill the trough portions to the level indicated at L in FIGURE 1. The supporting base 10 is further shaped to provide an upright side wall 14 mounting thereon a door or wall member 15 which may be vertically slidable to provide access to the operating parts of the grinding apparatus A.

The central portion 11 of the base or foundation 10 is contoured to support mounting means 16 in the form of a table or pedestal for conveying means generally designated as 17 and 18. The conveying means comprise a plurality of pairs of bracket members 19 and 20, which as indicated in FIGURE 3 may be mounted in end to end abutting relation. Each bracket member is provided with a flange portion 21 transversely slotted as at 22 to provide horizontal adjustment, each of the flange portions 21 receiving therebeneath shims 23 to permit vertical adjustment of the conveying means 17 and 18. The flange portions 21 receive therethrough screw means 24 threaded into the pedestal 16, and as shown, the shims 23 are slotted in the manner of the bracket flange portions 21. Suitable means are provided to continuously urge the bracket members 19 and 20 toward one another, and such means may take the form of springs 25, although of course other means can be used for this purpose. It will now be seen that the conveyor means 17 and 18 feature both vertical and horizontal adjustability, so that logs of varying diameters can be accommodated and at the same time sufficient forces exerted against the logs to effect compression thereof, whereby due to said compression the fibers of the logs are loosened and fiber removal during grinding facilitated.

Each bracket 19 and 20 of the conveyor means receives shafts 26 mounting conveyor rollers 27 and 28. The conveyor rollers are freely rotatable and are generally smooth surfaced, although at the inlet end of the apparatus A the rolls may be driven and may have grooves formed therein, as indicated by the numeral 29 in FIGURE 3, to assist in axial movement of the log therealong. As shown in FIGURE 1, the conveyor rollers 27 and 28 receive log W therebetween and are continuously in contact with the log periphery at a pair of spaced points thereabout. It is to be further observed from FIGURE 1 that the log W is submerged to approximately one-half its diameter in the treating solution, and that the conveyor rollers 27 and 28 are almost entirely submerged. By this arrangement, the log W is continuously subjected to the effects of the treating fluid, which functions to dissolve the lignins in the log whereby fiber removal is considerably facilitated.

The opposite side of the base 10 is provided with a relatively flat base surface 30 and erected therefrom is a pair of spaced stationary wall members 31 and 32. A plurality of pairs of wall members 31 and 32 are spaced along the length of the grinding apparatus A, and said members provide a pivotal support for each of the grinding units in the manner now to be described.

It is to be seen upon reference to FIGURE 4 that the stationary wall members 31 and 32 are turned inwardly at 31a-b and 32a-b to receive bearings 33 providing support for a pivot shaft 34. Corotatably mounted upon the pivot shaft 34 and spaced inwardly of the opposite ends thereof by the flange portions 31a-b and 32a-b is a sleeve portion 35 of a stop member generally designated at 36 and having a yoke portion 37 integral with the sleeve portion 35. At spaced locations thereon the yoke portion 37 is formed with a pair of stop portions 38 and 39, which cooperate with later described fixed structure on the wall members 31 and 32 to limit upward and downward movement of the grinding units.

Each wall member 31 and 32 may carry upon the inner surfaces thereof a rigidifying rib 31c and 32c, and it may be seen from FIGURE 4 that these ribs terminate

5 at one end at the flange portions 31a and 32a and at their opposite ends at flange portions 31d and 32d on the wall members 31 and 32. Secured by bolt means or the like 40 to the flange portions 31d and 32d are flange portions 41a provided on a fixed stop member 41. The stop member 41 may of course take many different configurations, and in the exemplary form illustrated in section in FIGURE 4 said stop member may have a downwardly bowed portion 41b connecting with the flange portions 41a and a generally upright portion 41c having a generally T-shaped stop portion 41d formed thereon.

10 The means to rotate the grinding units upwardly and downwardly in an arcuate path about the pivot point 34 between the positions of FIGURES 1 and 2 are preferably pneumatic, and may be seen to take the form of a pair of air cylinders 42 and 43. The cylinders 42 and 43 are attached at their inner ends to the opposite ends of the fixed stop member 41, and the opposite end of the cylinder 43 is attached for movement to a wall portion 44 connecting with the movable stop member 36. The opposite end of the air cylinder 42, on the other hand, is connected to a pair of spaced elbow or hinge members 45 and 46 integral with a cup-shaped housing portion 47, which itself is secured to or integral with the movable stop member 36 for swinging movement therewith. While the operation of the instant apparatus will be described in detail hereinafter, it may be noted at this point that the admission of air pressure to the air cylinder 42 15 rotates or swings the movable stop member 36 and structure connecting therewith in a counter-clockwise direction until the fixed stop portion 41d on the stop member 41 contacts or abuts with the stop portion 39 on the movable stop member 36. Inflation of the air cylinder 43, on the 20 other hand, causes movement as shown in FIGURE 2 to raise the grinding apparatus, and the extent of upward movement is limited by contact of the fixed stop portion 41c against the movable stop portion 38.

25 The spaced elbow members 45 and 46 receive therethrough a hinge or flange portion 48 (FIGURE 6) fixed to a plate member 49. The elbow portions 45 and 46 receive therethrough bolt means 50 and 51 having lock nuts 52 associated therewith, and as shall be described later, the elbow portions 45 and 46, the flange or ear portion 48 and the bolt and nut means 50-52 provide a fine tiltable 30 adjustment of the grinding units.

35 Mounted in face to face relation with the plate member 49 is a plate member 53 to which connects a motor bracket 54 supporting therein motor means 55, each of 40 which is provided with a shaft 56 carrying thereon a grinding wheel or surface 57, illustrated in its preferred form as generally conical.

45 The motor mounting plate member 53 is adjustably connected to the plate member 49 by means of a bolt 58 40 threadably received in the plate member 49 and passing through a flange portion 59 on the plate member 53. It may be noted from FIGURE 1 that the bolt means 58 is generally of lesser length than the threaded bore 60 receiving said bolt means, for the purpose of providing an 45 adequate range of vertical adjustment of the plate member 53 with respect to the plate member 49. Upon reference to FIGURE 5 it may also be noted that the plate member 49 has formed thereon a tongue portion 49a slidably in a groove 53a in the plate 53 to thereby provide guiding 50 means during vertical adjustment.

55 Upon reference now to FIGURES 1 and 6, it is to be observed that the plate members 49 and 53 are further attached one to the other by a plurality of bolt means or the like 60 threaded from the plate member 49 into the plate member 53. The plate member 49 is provided with a plurality of slots 61 therein which are of a length generally corresponding to the extent of adjustment of the plate member 53 relative to the plate member 49 by means of the bolt 58. The plate member 49 is shown in FIGURE 6 as canted or tilted toward the inlet end of the

grinding apparatus, and this annular displacement is preferred in order to similarly dispose the grinding wheel 57 to produce from the log W a relatively longer and thereby higher quality fiber.

Referring now again to FIGURE 5, the plate member 49 has formed thereon an outwardly extending annular portion 49b and 49c received between the inner wall surfaces of the cup-shaped housing portion 47. The housing portion 47 is provided with a pair of ear portions 47a and 47b passaged with slotted openings 47c therein receiving stud means or the like 62 to effect an attachment between the housing portion 47 and the plate member 49. The stud means 62 receive locking nuts 63 therein, the adjustment of which permit adjustment of the location of a particular point on the surface of the grinding wheel 57 with respect to the top center of the log W. This provides, among other advantages, a change in the particular portion of the grinding surface effecting a shredding action to reduce wear of the grinding surface. As is apparent, the relative length of the ear portion 48 received between the flange portions 45 and 46, and which means were described as effecting a fine tilting adjustment, is such that the plate member 49 and structure connecting therewith may be moved outwardly by the adjusting means 62 and 63 a sufficient distance without the ear portion 48 being out of contact with the bolt means 51 and 52 pressing thereagainst. Further, it may be seen from reference to FIGURES 5 and 6 that the slotted openings 47c in the ear portions 47a of the housing 47 are of sufficient width with respect to the diameter of the stud means 62 so that there is no interference when tiltable adjustment is effected by the ear or tongue portion 48, elbow portions 45 and 46, and bolt and locking means 50-42.

It was earlier noted in connection with FIGURE 1 that the side wall structure 15 provides a splash guard to prevent treating fluid and/or pulp from being cast into the area outwardly of said wall structure during the grinding operation. The side wall structure 15 may be vertically or horizontally movable to provide access to the grinding wheel 57, motor means 55 or other structure of the grinding apparatus A. In addition to the enclosure portion 15, the grinding apparatus A incorporates splash guard means which protects the motor means and the other structure described. In this connection, it may be seen from FIGURE 1 that the motor means 55, the plate members 49 and 53, the housing portion 47 and the pivotal connection 34 and means adjacent thereto are protected by an enclosure portion generally designated at 65.

The enclosure means 65 may comprise a top wall portion 66 connecting with a side wall portion 67 having an outwardly turned portion 67a which cooperates with a similar portion 68a on an inclined wall portion 68 to clamp therebetween rubbing seal means 69 which may be constructed of rubber. The enclosure means 65 further comprises a bottom wall portion 70 having an upwardly turned portion 70a in rubbing contact with seal means 71, also of rubber, and held between clamp means 72. One portion of the clamp means 72 attaches with a further wall portion 73 of the enclosure means 65, and it may be seen that the wall portion 73 curves downwardly to terminate at the upper wall surface 30 of the foundation 10. Welding techniques, screw means or the like may be employed to attach the various wall portions of the enclosure means 65 to the structure housed thereby.

Experience has indicated that the grinding wheel 57 should at all times during the shredding operation be maintained free of adherent pulp fibers, and for this purpose there is provided in this apparatus nozzle means 75 supported by the enclosure wall portion 70, and directed toward the grinding wheel surfaces to flush the same of fibers. Hot water is normally employed, although steam may also be utilized and the cleansing fluid may have a solvent added thereto to assist in loosening of the fibers during grinding. Normally, however, the solvent action would be performed by use of treating fluid in the trough

portions 12 and 13 in rolling contact with the conveyor rollers 27 and 28 and the log W supported thereby. In this regard, it may be found desirable to pressurize the trough to effect a chemical cooking of the pulp received therein. This can readily be effected by suitable strengthening of the trough structure and the enclosure means to withstand pressures of the order required. Pressurizing of the trough would then render unnecessary chemical cooking in a subsequent processing step, which would by conventional practices be performed in a location removed from the grinding apparatus.

While it is believed that the operation of the instant apparatus is apparent from the preceding description, a brief summary will now be given. The log to be ground, and from which the bark would normally be removed in an earlier processing step, is supported upon the free-wheeling rollers 27 and 28, and upon entry of the log into the grinding zone beneath the abrasive wheel 57, a rotational and axially advancing force is applied to the log by reason of the conical configuration employed. The conical grinding wheels 57 not only abrade the surface of the log in a generally helical fashion to a particular depth, but also compress the log surface to effect fiber loosening. Specifically, by virtue of the weight of the grinding wheel 57 and the motor supporting said wheel, as well as the connecting mounting structure, a substantial force is applied against the log to effect a compression, and as the log rotates in contact with and beneath the grinding wheels, a further compression is provided by the conveyor rolls 27 and 28. Accordingly, the log is subjected to an alternating compression and decompression, the latter action taking place on that portion of the log periphery which is not directly contacted by either the grinding wheel or the conveyor rolls. As stated, the weight of each grinding unit applies a substantial force, and additional compressive action may be imparted by the air cylinders 42, whereby a substantial loading is at all times present.

The grinding wheels 57 are preferably canted in the direction of the inlet end of the apparatus A to provide a more positive grinding action and to in effect lift the fibers from the logs during the grinding operation. The grinding wheels 57 rotate in a counter-clockwise direction to rotate and simultaneously axially urge the logs along the conveyor rollers 27 and 28 in free rolling contact therewith.

The force applied to the logs by the grinding wheels 57 may of course be varied by the air cylinders 42, so that a uniform compressive force is exerted regardless of the particular type of wood being ground. Further, should the type of wood vary or the initial diameter of the logs to be ground be different, a fine tiltable adjustment of the grinding wheels 57 with respect to the logs may be obtained by adjustment of the ear portion 48 with respect to the elbow members 45 and 46.

Additionally, a relatively greater depth of cut can be effected by vertical adjustment of the grinding wheels 57, and as earlier noted, this is accomplished by raising or lowering the plate member 53 with respect to the plate member 49 by means of the adjusting bolt 58, and further by means of the bolts 60 passing through the plate 49 into the plate 53. And as was noted, should adjustment in a generally transverse direction be desired to reduce grinding wheel wear, the stud means 62 can be varied to increase or decrease the distance of the plate member 49 relative to the housing portion 47.

The action of the novel stop means herein provided was earlier described, and it can be seen upon comparison of FIGURES 1 and 2 that inflation of the air cylinders 42 lowers the grinding wheels, motor means and all movable structure connecting therewith to a down or log engaging position. At this time, there is no air input to the cylinders 43, and the latter cylinders are only actuated when it is desired to raise the grinding units from the position of FIGURE 1 to that of FIGURE 2. When in the down position, the movable stop means 36, and par-

ticularly the stop portion 39 thereon, abuts against the fixed stop portion 41d on the stop member 41 to limit the downward movement. Raising of the grinding units by inflation of the air cylinders 43, on the other hand, is limited by contact of the movable stop portion 38 with the fixed stop portion 41d, as clearly indicated in FIGURE 2.

It may now be seen that applicant has provided grinding apparatus wherein the motor means and grinding wheel supported thereby are adjustable in a plurality of different planes, permitting the control of force applied for different types of woods and further permitting use of the apparatus with a wide variety of log diameters. Variation in log diameters is further accommodated by the vertical and horizontal adjustability of the conveyor means 17 and 18, so that at all times a constant compressive force is applied against the log W during grinding. All operating parts which might possibly be damaged by contact with the treating fluid are shielded by the enclosure means 65, and as well, splashing outwardly from the grinding zone is prevented by the wall structure 15. By provision of motor means for each grinding wheel independent control is achieved, whereby among other advantages each grinding station may be adjusted to particular conditions. Further, particular circumstances may render it desirable to operate only particular grinding stations, and this is readily accommodated by the apparatus herein disclosed. By this apparatus the logs are successively reduced in diameter and this is illustrated in FIGURE 3 which shows the sequential tapering grinding action performed by the invention.

It is to be understood that various changes and modifications may be effected in the apparatus disclosed without departing from the novel concepts of the present invention.

We claim as our invention:

1. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, and pneumatic means connected to the drive support means and to the stationary means to individually swingably move said support means in an arcuate path downwardly and upwardly to locate the grinding surface on said support means into and out of engagement with the logs.

2. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, motor means to drivingly support each of the grinding surfaces independently of the other grinding surfaces, mounting means for said motor means, support means connected to said mounting means, a movable stop assembly having stop means thereon and connected to the support means, stationary means having stop means thereon and pivotally mounting the movable stop assembly, and pneumatic means connected to the movable stop assembly and to the stationary means to move said stop assembly about its pivotal connection with the stationary means to swing the grinding surface, motor means, mounting means and support means in a raising and lowering direction, the movable stop means contacting the stationary stop means at the extent of raising and lowering directions to limit movement of the grinding surfaces.

3. Apparatus for grinding logs to produce pulp therefrom, comprising conveyor means for supporting the logs during travel along said conveyor, a plurality of individually operable grinding surfaces to abrade the logs

at spaced locations thereon and while said logs are supported by the conveyor means, means to drivingly support each of the grinding surfaces independently of the other grinding surfaces, stationary means pivotally mounting the drive support means, pneumatic means connected to the drive support means and to the stationary means to individually swingably move said support means in an arcuate path downwardly and upwardly to locate the grinding surface on said support means into and out of engagement with the logs, and means connected to the drive support means to vertically adjust said drive support means and the grinding surface thereon relative to the logs on the conveyor means.

4. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, pneumatic means connected to the drive support means and to the stationary means to individually swingably move said support means in an arcuate path downwardly and upwardly to locate the grinding surface on said support means into and out of engagement with the logs, and means connected to the drive support means to vertically adjust said drive support means and the grinding surface thereon relative to the logs on the conveyor means.

5. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, pneumatic means connected to the drive support means and to the stationary means to individually swingably move said support means in an arcuate path downwardly and upwardly to locate the grinding surface on said support means into and out of engagement with the logs, and means connected to the drive support means to adjust said drive support means and the grinding surface thereon in a generally transverse direction relative to the conveyor means.

6. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, pneumatic means connected to the drive support means and to the stationary means to individually swingably move said support means in an arcuate path downwardly and upwardly to locate the grinding surface on said support means into and out of engagement with the logs, and means connected to the drive support means to tiltably adjust said drive support means and the grinding surfaces thereon in generally the direction of swingable movement of the support means relative to the stationary means.

7. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, pneumatic means connected to the drive support means and to the stationary means to individually swingably move said support means in an arcuate path downwardly and upwardly to locate the grinding surface on said support means into and out of engagement with the logs.

8. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, pneumatic means connected to the drive support means and to the stationary means to individually swingably move said support means in an

arcuate path downwardly and upwardly to locate the grinding surface on said support means into and out of engagement with the logs, and enclosure means for the conveyor means and drive support means to prevent spraying of pulp into the areas adjacent the conveyor means to prevent damage to said drive support means.

8. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means mounting the drive support means, and pneumatic means connected to the drive support means and to the stationary means to individually move said support means downwardly and upwardly to locate the grinding surface on said support means into and out of engagement with the logs.

9. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, and actuation means connected to the drive support means and to the stationary means to individually swingably move said support means in an

30

arcuate path downwardly and upwardly to locate the grinding surface on said support means into and out of engagement with the logs.

5 10 15 20 25 30

10. Apparatus for grinding logs to produce pulp therefrom, comprising conveyor means for supporting the logs during travel along said conveyor, a plurality of individually operable grinding surfaces to abrade the logs at spaced locations thereon and while said logs are supported by the conveyor means, means to drivingly support each of the grinding surfaces independently of the other grinding surfaces, stationary means pivotally mounting the drive support means, actuation means connected to the drive support means and to the stationary means to individually swingably move said support means in an arcuate path downwardly and upwardly to locate the grinding surface on said support means into and out of engagement with the logs, and means connected to the drive support means to vertically adjust said drive support means and the grinding surface thereon relative to the logs on the conveyor means.
